UNITED STATES PATENT OFFICE.

WILLIAM F. LAUTENSCHLAGER, OF CINCINNATI, OHIO, ASSIGNOR TO LORENZ MUTHER,
OF NEWTON, MASSACHUSETTS.

EYELETING MACHINE.

Application filed August 5, 1921, Serial No. 490,099. Renewed April 19, 1928.

This invention relates to an eyelet-setting machine of a high speed power type, by which the stock is punched or pierced, fed for a determined eyelet spacing, the eyelet inserted through the punched opening in the stock and clinched in a single operating cycle of the machine.

Eyeletting machines of this class have almost universally been arranged with a punch-carrying head movable from a stock punching position to an eyelet inserting and setting position, for cooperating with relatively stationary eyelet-holding and clinching mechanism. The punch-carrying head is provided with a reciprocating combined tubular punch and anvil, the punch in one position of the head operating upon a stationary table or cutter block, and after a punching operation, by the movement of the head, is positioned over the eyelet-holding and clinching mechanism. The holder comprises a reciprocating spindle, which concentrically receives the eyelet, and the clincher, as a reciprocating sleeve telescoping over the spindle, is adapted to cooperate with the anvil portion of the punch. For an efficient operation of the machine and perfect eyelet-setting, it is essential that absolute alignment and registration of the opposing cooperating parts be maintained, for the slightest disalignment will result in either injury to the punching and setting tools or to the eyelets. The eyelets used in high speed machines are usually of a very soft ductile material, and are more susceptible to injury through disalignment and non-registration of the tools than the tools which are of hardened steel. In high speed machines, having the working parts as mentioned, vibration and bearing play of the parts renders it mechanically impossible to effect the necessary alignment and registration of the opposing eyelet-setting tools, and results in the frequent breaking of the tools and constant imperfect eyelet-setting, as clinching the eyelet more on one side than on the other, and not annularly uniform, and when the eyelets are enamel finished, as generally used in shoe uppers, the enamel coating is marred and chipped.

In the present invention, the opposing co-operating tools are supported and reciprocated in a unitary frame structure in constant registration, and the tools move unitarily with their supporting frame or carrier with any lateral or transverse motion of the same.

The carrier is translated from a punching position to a predetermined eyelet spacing distance for a work feeding operation and to move the tool beyond a stationary cutting table or block.

An object of the invention is to eliminate the above mentioned objections of imperfect eyelet-setting, and relatively slow machine operation, by providing a unitary tool carrying frame.

This results in an increase in the life of the punching and eyelet-setting tools and a perfect eyelet-setting, and also enables the machine to be operated at a considerably higher rate of speed than heretofore.

Other objects are to simplify and improve the adjustment of the punching and setting tools, to coact eyelet-setting positions, and to simplify and improve the adjustment of the combined punch and anvil for its proper contact with the punch block.

An additional object is to permit the convenient and rapid removal of either or both, combined punch and anvil, and eyelet holder and clincher for purposes of substituting other types of the same, or for any other purposes whatever.

Another object is to provide a manually operated feed adjustment, enabling a rapid feed change, to give alternate short or long eyelet spacing, at the will of the operator.

Another object of the invention is the provision of means whereby the eyelet holder is caused to move at different speeds during different portions of its cycle of movement. From its normal or starting position the eyelet holder is caused to move slowly to its eyelet engaging position in order to secure proper engagement with the eyelet held yieldingly at the end of the raceway; then after the eyelet has been delivered the eyelet holder moves at an increased rate of speed to the point at which the setting of the eyelet is to take place and after that has been accomplished the eyelet holder then returns to its initial or starting position at its greatest rate of speed.

Another object is to provide for the convenient attachment and removal of the eyelet reservoir and raceway for purposes of substitution, as the requirements for different styles of eyelets may demand.

Fig. 1 is a general perspective view of my improved rapid eyeleter.

Fig. 2 is a vertical longitudinal section taken approximately on line 2—2 of Fig. 3.

Fig. 3 is a horizontal plan section, approximately on line 3—3 of Fig. 2.

Fig. 4 is a vertical transverse section approximately on line 4—4 of Fig. 2.

5 Fig. 5 is a section on line 5—5 of Fig. 3.

Fig. 6 is a fragmentary side view of the raceway side of the machine.

Fig. 6^a is a detail section on line 6^a—6^a of Fig. 6.

10 Fig. 7 is a diagrammatic vertical section showing the manner of removing or replacing the upper and the lower sets of tools.

Fig. 8 is a diagrammatic plan section showing the construction and operation of the 15 feed and feed-change mechanisms for moving the tool carrier laterally.

Fig. 9 is a detail side elevation of the feed yoke and of the feed cam for transversely translating the tool frame placed in its initial 20 position in relation thereto and to the punch reciprocating cam, shown in dot-and-dash lines.

25 Figs. 10 and 11 are respectively side and end elevations of the slide bar fulcrum head, and depending pivot, integral therewith, for varying eyelet spacing.

30 Figs. 12 and 13 are respectively a detail edge elevation and plan of the adjustable three pieced link for connecting the cam engaging feed yoke to the right end of the pivot slide bar.

Fig. 14 is a detail plan of the pivot slide bar.

35 Figs. 15 and 16 are respectively a detail plan and side view of the toggle link for preventing lateral movement of the pivot slide bar.

40 Fig. 17 is a face view of the eccentric shaft and attached disk, and eccentrically mounted pin, for operating the vertically reciprocating eyeletting tools.

Fig. 18 is a face view segmental eccentric block engaged upon the eccentric crank pin.

Figs. 32, 33, 34 and 35 are diagrammatic views showing the punching, feeding and setting operations.

Fig. 36 is a section on line 36—36 of Fig. 3 illustrating the clutch mechanism.

Figs. 37 and 38 are respectively fragmentary detail face and sectional views of pulley hub construction.

Fig. 39 is a plan view of a modified form of punch block used when setting eyelets in "military stays".

Fig. 40 is a longitudinal section on line 40—40 of Fig. 39.

Fig. 41 is a view similar to Fig. 39, showing the manner of guiding the stock.

Fig. 42 is a detail section on line 42—42 of Fig. 41, showing the "stay" strip inserted in the grooved pivoted punch block.

In the drawings, the casing, housing or support for the mechanism is generally indicated at 1. The main drive shaft is shown at 2, (see Fig. 3), is supported in elongated bearings 3 and 4, and extends to the right beyond the casing 1, to support the drive and clutch pulley 5, and part of the clutch mechanism, all hereinafter described in detail.

The reciprocating punching and eyeletting tools are arranged in cooperating opposing positions, as upper and lower, and are respectively mounted in relatively opposite bearings of a laterally translatable head or frame of yoke design, to provide a work-receiving throat between the opposing upper and lower tools. The head unitarily supports the tools for constantly maintaining their operating alignment and registration irrespective of any lateral translation of the head.

The tools are reciprocated by the following mechanism, (see Figs. 2 and 3.)

105 Mounted upon the main drive shaft 2, at its inner extremity, is a disk or rotor 6, having upon its inner surface a semi-circular eccentric groove 7, (see Figs. 2 and 19) the center 8 of which is eccentric to the axial center 9 of the shaft 2, the center line 10 of the groove 7 passing through the axial center 9 of the said shaft 2. A segmental or semi-circular eccentric block 11 is slidably mounted within the eccentric groove 7 of the rotor and the said block has an opening 12, (see Fig. 18), near one of its extremities, through which a pin 13 extends. This pin is eccentrically carried by a disk 14, mounted upon a shaft 15, the axial center of which is in vertical alignment with the axial center of the shaft 2, but horizontally below and eccentric to that shaft.

110 The shaft 15 is supported in a hub bearing cap 16, secured to the left side of the casing 1 as a closure for the port opening through the casing, through which the crank disks are inserted for assembling the parts in connec-

tion with the main shaft 2. The disks 6 and 14 are spaced apart to receive a connecting link 17 therebetween pivoted upon the crank pin 13, carried by the disk 14 and engaged into the slide block 11, slideable in the grooved face of the disk 6. The connecting link 17 has an opposite forked end 18, pivotally connecting with the rock lever 19, fulcrumed upon the cross shaft or rod 20, supported in the 10 bearings 19^a of the casing 1.

The forward end 21 of the lever 19, is offset laterally, (see Fig. 22), and its end forked as at 22 for the reception of, and pivotal connection with a turn buckle block 23, the said 15 block and fork arms being traversed by a pivot 24. The block 23 is provided with an upstanding right threaded stem 25, designed to coact with the corresponding threads of a turn buckle adjusting nut 26, the upper portion 20 of the nut having left threads for coaction with a correspondingly left threaded stem 27, projecting downwardly from a turn buckle block 28, pivoted at 29 to a slide member 30. The slide member 30 is sustained in guides 31, formed at the front and as a part 25 of the casing, and is capable of vertical reciprocation therein. Gib plates 32, pivoted at 33 to the guides 31, hold the plunger 30 in position within the guide-way. The plates 30 are provided near their upper ends and on their inner opposing edges with slots 34, these 30 slots being concentric with the pivots 33 and traversed by winged clamping screws 35, for holding the plates in their proper positions. 35 Fastened upon the upper outer edge of the plunger 30 is an anchoring plate 37, in the form of an angle-iron, the horizontal edge of which engages a notch 38, of the lower tool-carrying plunger 39, the bottom of which rests upon the slide member 30. The knurled nut 26 is provided on its lower circumference with teeth 40, engaged by a pawl spring 41, to hold the nut in its adjusted position.

When it is desired to raise or lower the 45 plunger to adjust the tool plunger thereupon, the knurled nut 26 is rotated, and by its turn-buckle action micrometrically adjusts the slide member and its connecting parts, either upward or downward, as may be required.

When it becomes necessary to remove the 50 tool carrying plunger, the winged clamping screws 35 are loosened and the plates 32 swung outwardly and downwardly about their pivots 33, to a horizontal position, to bring their lower edges in vertical alignment and flush with the inner vertical faces of the 55 guides 31, releasing the slide member 30, for permitting the lower end thereof to be pressed slightly outwardly by the action of the spring 41 and disengaged from the guides 31, and adapting the member to be swung downwardly about the pivots 24 and 29, to a 60 position shown in Fig. 7, disengaging the anchoring plate 37 from the notch 38 of the

tool plunger 39. The tool plunger 39 is slidably held in the bore 50 of a laterally translatable tool supporting head 51, traversed by and rigidly attached to a lower guide bar 52, capable of reciprocation in bearings 53 and 54 of the casing 1, and traversed by and slideable upon an upper stud shaft 55, rigidly held at 56 in the casing 1, to support and guide the upper portion of the tool supporting head 51.

The head 51 is of yoke design, providing upper and lower opposite aligned tool supporting and guiding arms, and for unitarily carrying the tools in the lateral translation of the head for feeding the work over a punch-block or table, for a definite eyelet spacing in the work. A bore 57^a in the upper arm of 75 the frame or head 51 slidably receives the tool plunger 57, the bores 50 and 57^a being always in vertical alignment to assure absolute alignment and registration for the opposing cooperating tools, essential to an efficient operation of the parts at high speeds, and to a perfect setting and clinching of the eyelets, without injury to the tool or eyelets.

The upper tool-holding plunger 57 is provided with a notch 60, at its rear side, into which the edge of a guide and anchoring plate 61 projects, the plate being rigidly attached to forward arm 63 of the upper rock lever 62, having a bore 63^a, traversed by an eccentric bush bearing 64, which in turn is traversed by a removable shaft 65, the said shaft being slidably held in bearings 66 and 67 at the upper forward side of the casing 1, above and rearwardly of the stub shaft 55. The eccentric bush bearing 64 on its right end is provided with a crank arm 65^a, having at its outer extremity a spring pressed detent pin 65^b, designed to engage with any of a series of openings 65^c, provided in a quadrant plate 68, integral with the upper tool actuating 90 lever 62. When the detent pin 65^b is withdrawn from one of the openings 65^c, and the arm 65 rotated forwardly, the action of the eccentric bush bearing 64 lowers or adjusts the lever 62, and consequently, its connected 95 tool holding plunger for vertically adjusting the upper set of tools.

When it becomes necessary to remove the 100 upper tool-holding plunger 57, as for substituting a different kind or size of tool, the shaft 6 is withdrawn from the bearing 67, and from the bore of the eccentric bush-bearing 64, allowing the lever 62 to be swung upwardly about the pivot 70 of the toggle link 72. This disengages the anchoring plate 61 from the notch 60 of the tool-holding plunger 57 and allows its withdrawal from the head. The shaft 65 may then be reinserted within the bearing 67, to form a rest for the lever 62 in its raised position. The operation of 105 replacing the combined upper tool-holding plunger is thought to be obvious from the above description of the reverse operation.

The mechanism for actuating or reciprocating the upper tool-holding plunger comprises the following parts.

The arm 63^b of the lever 62 is pivotally attached by a pin 70, to the upper fork 71, of a double forked toggle link 72, the lower fork 73 of which, straddles the forked arms 75 of a forked toggle 76 rotatively mounted upon a shaft 77, which shaft is in turn mounted rotatively in bearings 78 and 79 of the casing 1, extends outside of said casing, is provided at its left outer end with an adjustable lever arm 80 and at its right end with an eyelet raceway tripping roller arm 81, (see Figs. 1 and 3), the lever arm and tripping arm functioning to throw the eyelet raceway from operative or feeding position in respect to the set spindle 39^a as hereinafter more fully described. The forks 73 and 75 are traversed by a pivot pin 85, provided on its left end with a presser foot tripping disk 86, (see Figs. 2 and 3), functioning to raise the presser-foot or work clamp during the forward movement of the toggles 72 and 76, the presser-foot overhanging a work table or punch block for holding the work during a punching or perforating operation. The pivot pin 85 also traverses the head 87^a of a stem 87, having adjustable threaded engagement with a yoke 88, the said head 87^a being placed between the arms 75 of the forked toggle 76, the opposite arms 89 of the yoke 88 connecting with the pitman 95 as a member converting rotary motion into reciprocating motion for reciprocating the upper tools. The said arms 89 are pivotally attached to the pitman by a pin 96. The pitman 95 is mounted adjacent the disk 6 for horizontal reciprocative movement upon grooved slide blocks 97, rigidly held upon cross bars 98, placed transversely of, stepped in and extending to the right beyond the frame 1, and upper and lower arms 100 at opposite sides of the pitman 95, engage the upper and lower grooves 97^a of the blocks 97, to permit of the reciprocative movement of said pitman 95. The body of the pitman 95 is of rectangular frame-like configuration and upon the opposite inner faces of the same; bearing gibs 101 are fastened, which engage the rotative cam 105, fastened to the disk 6, and movable therewith. The cam 105, (see Figs. 2 and 3) moving with the disk 6 as a result of the rotation of the shaft 2, reciprocates the pitman 95, transmitting motion to the yoke 88, stem 87, toggles 72 and 76 and lever 62, to cause the upper tool 57 to successively punch the stock, release the punch from the punch plate and subsequently assist in the setting of the eyelet, a more detailed description of the operation of which will be given hereafter.

The following means are employed for reciprocating the tool carrying head 51, (see Fig. 8).

65 A feed cam 110 having a hub 111 is rigidly

mounted upon the main drive shaft 2, between the bearings 3 and 4 and is set upon the said shaft 2 in such angular relation to the cam 105 as will allow the cam 105 to cause the upper tool 57 to punch the stock and to then be slightly raised from the punch block before the feed cam 110 and its correlated mechanism, moves the tool carrying head to the left a predetermined distance, preparatory to the eyelet setting operation. The feed mechanism and its operation is best shown in Figs. 4 and 8. The feed cam 110, rigidly mounted as before mentioned upon the main drive shaft 2, coacts with the gibs 112 of a pitman 113, similar in construction to the pitman 95, mounted parallel therewith and sliding in grooved slide blocks 114, mounted upon the cross bars 98, in a manner exactly similar to the pitman 95. A three-part link 116 pivotally connected with the under side of the pitman 113 by a screw pin 117, (see Fig. 5), engaged through the head of the left threaded socket piece 118 of said link 116. The left threaded socket of the part 118 is engaged by the corresponding left threaded end of an adjusting rod 119, having a central squared portion, and having its opposite end provided with a right thread engaging a correspondingly threaded socket of the yoke section 120.

The inner surfaces of the arms of the yoke section 120 engage the outer surfaces of the arms of a forked link 121, and a pivot 122 traverses the arms of the yoke section 120, the arms of the forked link 121, (see Figs. 4, 15 and 16), and the outer end 123 of a pivot slide bar 125, the said end 123 being disposed between the arms of the forked link 121, the opposite end of which is pivoted to the guide bracket 137, as at 121^a. The swinging link 105 bar 125 is mounted for sliding movement in a groove 126 of a fulcrum head 127 and is held within the groove 126 by a cap plate 128, suitably fastened to the head by screws 129. The fulcrum head 127 is integral with a vertical pivot 130, rotatively held in a vertical central bearing 131 of a cross slide bar 135 mounted for sliding motion in guide brackets 136 and 137 attached to the outside of the casing 1. The cross slide bar of carriage 135 is capable of transverse or longitudinal movement in either direction to move the fulcrum head 127, to change the fulcrum of the swinging link bar 125, the left end 140 of which projects beyond the fulcrum head 127 and is connected by the pivot 141 to the forked end 142 of a link 143, the opposite end of this link being pivoted at 145 to the lower arm 146 of a vertically disposed shaft 147, mounted rotatively in bearings 148 and 149 projecting from the casing 1. From the upper part of the shaft 147 projects an arm 149, forming an obtuse angle with the arm 146, and having a link 150 pivoted thereupon at 151, the opposite end of said link being piv-

oted to the under side of the tool carrying head 51. The outer end of the forked link 121 is pivoted to the upper side of the guide bracket 137, as at 121^a, the said link acting to prevent lateral movement of the swinging

link bar 125 during the forward and rearward movements of the pitman 113 and of the link 116 connected therewith. As before stated, the cross slide bar 135 is laterally slideable in the guide brackets 136 and 137, to change the fulcrum point of the swinging link bar 125. As shown in the drawings, the carriage 135 and its fulcrum head 127 are positioned to give the ordinary minimum length of work feeding throw to the head 51. In order to increase the length of feed for setting the eyelets at a maximum distance apart, the carriage 135 is moved to the right to change the position of the fulcrum block 127 and manually operated means is provided to move the carriage and to limit this movement, a description of which follows.

Pivottally attached as at 160 to a lug on the guide bracket 136 (see Fig. 4) is an arc shaped lever 161, the lower end of which is pivoted at 162 to a link 163 and the opposite end of this link is pivoted at 164 to a lug 165, cast upon the under face of the carriage 135. To the upper outer end of the arc shaped lever 161 (see Fig. 4) is pivoted at 166, a rod 167, suitably connected with a foot treadle (not shown). The operator depresses the rod 167 and with it the lever 161, and, as a result, forces the carriage 135 to the right, (Fig. 8), left, (Fig. 4), to a distance determined by the adjustment of a set screw 170, mounted at the end of the carriage 135, and coacting with the guide bracket 136, the carriage being returned and maintained in its initial position by the action of a spring 171, the terminals of which are fastened at 172, 173 respectively, to the casing 1 and carriage 135.

An adjustable stop 174 is provided at the right end of the carriage 135 (Fig. 8), to limit the movement of the carriage against the action of the spring 171, the said stop coacting with the outer surface of the guide bracket 137.

The operation of the feed mechanism will be obvious from an inspection of Fig. 8, wherein dot-and-dash lines show the positions of the various feed elements when the tool carrying head 57 is positioned for an eyelet-setting operation. In virtue of action of the feed mechanism above described the spacing of eyelets can be quickly and accurately varied, and alternate long or short spacing can be accomplished by simple adjustment of the stop screw 170, in conjunction with the depression of the lever 161, to change the fulcrum point of the slide bar 125. When it is desired to alternate from short to long spacing, the carriage is shifted by the actuation of the lever 161 and when a

short spacing is again desired the lever 161 and carriage is released, whereupon the spring 171 automatically returns the carriage 135 and its fulcrum head 127 to the initial position.

The length work feeding stroke of the tool carrying head can therefore be varied at the will of the operator, while the machine is in motion, within predetermined limits permitted by a maximum movement of the carriage 135, for which the carriage was set by the stops 170, 174. To exemplify this feature, let it be presumed that the maximum movement for the tool head feeding stroke is two inches, and for such maximum stroke the set screw 170 outward, to permit the stop plate on the left end of the carriage, (Fig. 8), to strike against the machine frame or carriage bearing bolted upon the frame. The lever mechanism in connecting the tool head with the pitman would then throw the head in each revolution of the cam 110 or full reciprocation of the pitman 113 a full maximum stroke of two inches, as long as the operator kept the lever 161 depressed or the carriage positioned to its extreme right limit. The carriage could be permanently set in such position by set screw 174, if occasion required, or the spring 171 removed, which would permit the carriage to remain in any adjusted position.

The parts are designed for a constant minimum distance of head feed reciprocation, for moving the tools to an appropriate position over the table or cutter block, which, in this instance, is stationary for a work perforating operation, and to an appropriate position clearing the table, a cutter block for an eyelet inserting and clinching operation. If the cutter block was movable, the minimum head movement would not be required. The minimum punch block clearing movement may be said to measure one quarter of an inch. The operator therefore can at random change the reciprocating stroke of the head corresponding to the degree he moves the carriage 135, so that the head can have a reciprocating stroke of its minimum one quarter inch to any degree up to its maximum two inches. The maximum for manual treadle control is fixed by the degree of stop adjustment of the stop screw 170. Therefore, if a maximum head stroke of one inch is desired, the stop screw 170 is adjusted inward a desired amount for definitely limiting the sliding movement of the carriage 135 appropriately for a one inch stroke of the head, while its minimum stroke remains constant. The adjustment of the stop screw 174 is primarily for bringing the head to a return limit or normal position at an appropriate point over the work table or punch block.

Shifting the carriage, changes the pivot axis of the swinging link 125, thus increasing or decreasing its lever motion transmission

to the parts connected to its free end. The fulcrum for the link 125 when moved toward the end of the lever connecting yoke 120, of the connecting rod, increases the arc of movement at the opposite end of the link, increasing the head stroke and conversely when the fulcrum is adjusted in an opposite direction. The cam throw and pitman stroke is constant and the head stroke variable.

10 This is of considerable advantage when applying the eyelets upon shoe uppers, as it enables the operator to change the eyelet spacing while the machine is operating at high or full speed, it being desirable to change 15 the eyelet spacing at curved portions from the spacing toward the upper end of the upper or lower end.

The work is supported upon a table comprising an attaching base 181 (Figs. 1 and 2) 20 provided with a lug 182 upon its under face, the same resting within a corresponding groove 183, formed in a projection 184, at the front right side of the casing 1 and held therein by a headed screw 185. The base 181 25 is formed with a projection 186 extending upwardly and horizontally across the casing 1, between the upper and lower tools of the head, and is supported at its outer end upon a shoulder 187 at the opposite side of the casing 1. Extending forwardly from and forming 30 a part of the projection 184 is a horizontal work rest or table 188, having a slot 189 formed lengthwise there across, this slot being so positioned in respect to the upper and lower 35 tools as to permit them to centrally traverse the slot, during the work feeding and eyelet-setting operation. The slot 189 is of sufficient length to allow the tools to traverse the same at the maximum stroke of the tool carrying 40 head 51. The punch block 190 is countersunk within the work rest 188 and positioned beneath the punch and set 57, when the tool carrying head 51 is in its normal position, the upper surface of the said block 190 being 45 slightly below the upper surface of the work rest, in order that, after the stock has been punched and the punch has been released, and after tool head has moved to its eyelet-setting 50 position, the shank 191 of the upper tool 57 will in its downward movement to meet the set, be forced into the opening in the stock to 55 positively and more rigidly hold the same against the upper surface of the work rest 188. A slotted gage 193 is adjustably fastened by a screw 194 to the upper surface of the work rest 188 rearwardly of the tool 57, and provides a notch 195 at its forward end, into which the edge of the stock is inserted to 60 guide the same. A presser foot 200 of U-shaped formation surrounds the slot 189, and contacts the work rest 188, or the upper surface of the stock when the machine is in operation. The U-shaped presser foot 200 is open at its right, and at its back is provided with 65 a rearwardly extending lever arm (Fig. 2)

201, fulcrumed to the casing 1 as at 202, the opposite end of this arm being formed for coaction with the tripping disk 86, mounted upon the pin 85, pivotally connecting the forks 73 and 75. A spring 204 is attached at 205 to the lever arm 201, forwardly of its fulcrum 202, and at 206 to the casing 1, the action of this spring being to hold the presser foot upon the stock. In the drawings the presser foot is shown in the position it would occupy when the stock is beneath it, although the stock has been omitted for clearness of illustration. A rod 207 traverses the coils of the spring 204 and abuts the spring attachment screw 205, extends downwardly therefrom to 80 a lever treadle (not shown) and functions to raise the presser foot for insertion or removal of the stock.

Directly following the punching operation, the tripping disk 86 coacting with the end of 85 the lever arm 201, raises the presser foot to allow the feeding of the stock and immediately before the setting operation, the disk 86 recedes to allow the presser foot to engage the stock during the setting operation. The 90 above result is accomplished by the movement of the toggles 72 and 76, the ends of which are traversed by the pivot pin 85 carrying the tripping disk 86.

Eyelet magazine.

An eyelet raceway plate is generally indicated at 300; (see Figs. 1, 2, 4, 6 and 6^a) and rests slidably upon an incline shelf 301, which is fastened as at 302 to the right vertical outer 100 face of the casing 1, and slants upwardly and rearwardly and projects beyond and above the level of the top of the casing 1. The under surface of the raceway plate 300 slidably rests upon the upper surface of the inclined shelf 105 301, allowing the said raceway plate to be swung laterally toward the right, to prevent the engagement of eyelets by the set spindle, all to be more fully described hereafter.

At the upper under face of the shelf 301 110 is formed a casing 304, having provided therein, horizontal bearings 305, and a vertical bearing 306. In the bearings 305 is held a rotatable drive shaft 307, having a drive pulley 308 rigidly fastened thereto and adjacent to the pulley 308 is mounted a second idler pulley 309, the pulley 308 being belted to the power shaft (not shown). Between the bearings 305 and rigidly fastened to the shaft 307 is a worm gear 310, engaged with 115 a second worm gear 311 attached to a shaft 312, rotatable within the bearing 306. The upper end of the shaft 312 has formed upon it a peripheral retaining flange 313, resting in a socket 314, of the casing 304, and the upper end of the shaft is also provided with a relatively shallow cylindrical bore 315, diametrically traversed by a pin 316, the function of which is to engage the lower slotted end 317 of a brush spindle 318, hav- 120

ing a circumferential flange 319, whose under surface engages the upper surface of the shaft 312 and rests thereupon, the said flange being seated in a depression 320, formed in an annular boss 321 upon the under surface of the eyelet raceway plate 300 to form a pivotal bearing for the said raceway plate, and the said boss 321 is in turn seated within a depression 322 of the casing 304. The brush spindle 318 traverses a bearing opening 323, concentric with the annular boss 321. The brush-spindle is positioned at the rear of and slightly to the left of the axial centers of the punch and anvil 57 and clincher 39, and its lower end and that of the boss 321 form pivots about which the eyelet raceway plate is swung to displace its eyelet delivery end, to prevent the set spindle from engaging an eyelet. The brush-spindle and the 20 boss 321 act as a means for anchoring the raceway plate and for allowing a pivotal movement of the same, and permit of the ready removal of the said raceway plate from engagement with the drive means. The bore 25 of a circular brush-hub 325 is traversed by the brush-spindle, the under surface of said hub resting upon the upper surface of the raceway plate 300, being counterbored at 326 on its under side, to receive a washer 327, which washer is designed to rest upon a shoulder 328 of the brush-spindle, and to contact the wall of the counterbore as shown. A broad headed screw 329 by threaded engagement with the upper end of the brush-spindle, holds the brush-hub in position, and fastens the brush-hub for movement with the brush-spindle. Brushes 330 are provided at the periphery of the brush-hub and function to carry the eyelets to openings (not shown) 35 at the right of an eyelet receiving reservoir 281 surrounding the brush-hub and into which the eyelets are introduced through an opening at the top, the opening being closed by a hinged lid 232. As best shown in Fig. 1, the eyelets are delivered from the right side of the reservoir into the raceway 233, down which they are guided to the delivery point, the lowermost eyelet, when the raceway is set for delivering eyelets, being in a position to be engaged by the set spindle, the said lowermost eyelet being yieldingly held from leaving the raceway, by a spring actuated eyelet retaining finger 234, placed adjacent the delivery end of the said raceway. The raceway plate 300, at its inner mid portion, is housed within a groove 235, formed as a part of the casing 1, (see Figs. 4, 6 and 6^a), and means is provided upon the lower side of the raceway plate for adjusting the delivery end of the raceway for the proper positioning of the lowermost eyelet therein, above and in vertical alignment with the set spindle. This means comprises a downwardly projecting lug 236, having fastened thereto by a screw 237 a cylindrical projection 238, the said projection traversing an arcuate slot 239, in the shelf 301, the said slot being concentric with the center of the brush-spindle 318. Traversing said lug and threadingly engaging the same is a set screw 240, abutting the face of the casing 1 and having a lock nut 241 for holding the set screw in its adjusted position. A spring 242, attached at its lower end to the casing 1 and with its upper terminal engaging a notch in the outer edge of the raceway plate, forces and holds the end of the set screw 240 against the casing, allowing yielding lateral motion of the raceway. A handle 243, attached to the upper end of the spring 242, is provided for disengaging the spring to allow the removal or lateral swinging of the raceway plate when desired. Manually operated means for throwing the raceway outwardly, for the non-delivery of eyelets is provided, of which a description follows.

The shaft 77, rotatively mounted in bearings 78 and 79 of the casing 1 and projecting beyond the casing at both sides, is provided, as before stated, with an adjustable lever arm 80, having an opening 80^a at its outer extremity for engagement with a hook 80^b, forming part of a short chain 80^c, the end of which is fastened to the pivot 166 of the arc shaped lever 161. The opposite end of the shaft 77 has the raceway tripping arm 81 rigidly attached thereto, which arm extends upwardly and forwardly to a point adjacent the under side of the raceway plate and is provided at its extremity with a beveled edge 81^a for engagement with a roller 81^b rotatively fastened to the under side of the raceway plate 300. The tripping arm 81 is further provided with a projection 81^c to the outer end of which is slidably fastened the upper end of a link 21^b, the lower end of which is pivoted to a stub pin 21^c, projecting from and fastened to the right side of the arm 21 of the set lever 19. The upper end of the link 21^b is slotted as at 21^d and the slot is traversed by a headed screw 21^e, the bottom of the screw shank contacting the lower end of the said slot 21^d, the said lower end of the slot being held against the screw by a spring 21^f attached to the screw 21^e and to the link 21^b, the said link 21^b acting to raise the tripping arm 81 to throw the raceway to the right immediately after the set spindle has engaged an eyelet and for the purpose of releasing the eyelet from the raceway against the action of eyelet retaining finger 234. The portion of the slot 21^d extending above the screw 21^e allows an independent upward movement of the raceway tripping arm 81 against the action of the spring 21^f, when it is desired to temporarily interrupt the feeding of eyelets for any reason whatever, and this independent displacement of the raceway

is accomplished by inserting the hook 80^b into the opening 80^a of the lever arm 80, when, by depressing the arc shaped lever 161 by means of the rod 167, the lateral displacement of the 5 raceway is obtained, for the non-delivery of eyelets.

The detailed operation of the stock punching and eyelet-setting operations can best be understood from an inspection of Figs. 2, 32, 19 33, 34 and 35, the four latter views being in diagrammatic form.

The initial position of the mechanism for performing the above-mentioned operations is shown in Fig. 2, wherein the upper tool-holder 57 is at its upmost limit and the lower tool holder 39 at its lowermost position. Upon rotating the main drive shaft 2 in the direction of the arrow through an arc approximately 90°, two operations are simultaneously performed, (see Figs. 2, 32 and 33). The cam 105, coacting with the pitman 95, throws the pitman forwardly to force the toggles 72 and 76, also forwardly, bringing the axial center of the pin 85 in vertical alignment with the axial centers of the pivots 70 and 77, of respectively the upper rock lever 62 and toggle 76, to actuate the rock lever 62, forcing the upper tool holder and its tools downwardly to punch the stock, a continued movement of the pitman 95 forcing the pin 85 forwardly, out of vertical alignment with the pivots 70 and 77, raising the tool holder slightly to bring the punch off of the table cutting block preparatory to the feed operation.

35 The punch, in its descent punching through the material on the punch block, has its descent regulated for coming to a stop when the punch engages the punch block, thus causing complete punching without injury to the 49 punch or punch block.

Simultaneously with the above described operation, the disk 6 and segmental eccentric block 11, sliding in its groove 7, and connected by the eccentric pin 13, of the disk 14, to the 45 set lever link 19, operates to raise the outer forward end 21, of the lever 19, for operating the lower tools, to move the lower plunger 30 and tool holder 39 resting thereon upwardly for threading the eyelet feeding and guiding 50 spindle through an eyelet at the end of the raceway, and positioning the eyelet for driving the same through the perforation in the work, and subsequent clinching. The eyelet feeding and centering spindle is yieldingly 55 sustained in the holder.

The eccentric action of the disk 6 and its related parts causes a relatively slow movement of the pin 13 during the first quarter revolution of the said disk, with a correspondingly slow upward movement of the lower tool holder 39 to eyelet engaging position, thus insuring the proper tool engagement with said eyelet. After engagement with the eyelet, the upward speed of the tool holder 65 gradually increases and immediately after

the setting operation, the downward speed of the holder is extremely rapid, thus avoiding the possibility of collision with the work rest or with the eyelet raceway, since the tool head 51 moves directly after the said setting operation.

The continued rotation of the disk 6 and cam 105, (see Figs. 34 and 35), through an arc of approximately 116°, during which rotation the tool carrying head 51 has moved to the left, (see Fig. 36), acts to force the upper tool to eyelet clinching position by causing the axial center of the toggle connecting pin 85 to move rearwardly, and again become vertically aligned with the pivots 70 80 and 77; to eccentrically force the block 11 and pin 13 downwardly, and to raise the punch to setting position, as shown.

During the continued rotation of the disk 6 through an approximate arc of 154°, the 85 combined punch and anvil 57 and lower tools 39 are quickly released, the tool holder 39 traveling rapidly downwardly to its normal position, as above described, and the upper tools 57 also assuming their uppermost position through the action of the cam 105.

As the pin 85 travels forwardly with its connected toggles, the tripping disk 86 engages the rearward extension of the arm 201, to raise the presser-foot immediately after 95 the punching operation, preparatory to the movement to the left of the tool carrying head. As the pin 85 travels backwardly, (see Fig. 34) to bring the punch and anvil to setting position, the lever of the presser-foot 100 is released and the presser-foot is forced against the stock by the spring 204, firmly holding the same during the setting of the eyelet therein.

Drive and clutch mechanism is disposed at 105 the right of the casing 1, in principle of operation corresponding to some clutch mechanism, disclosed in an application, Serial No. 331,090, filed by me on October 16, 1919, now Letters Patent No. 1,439,314, issued Dec. 19, 1922; and the clutch mechanism is classifiable 110 as a distinct and separate improvement from the invention herein. Only an inferential disclosure will be made of the details of construction thereof as is necessary for the 115 proper understanding and operation of the machine as a whole.

Referring to Figs. 1, 3, 36, 37 and 38, the 120 drive and clutch pulley 5 is shown loosely and rotatively mounted upon a cylindrical hub member 400, rigidly attached to the shaft 2 by a pin 401. The bore 402, of the clutch and drive pulley 5, has formed upon its inner surface and at the outer edges of the same, shallow segmental depressions 403, their 125 inner surfaces being depressed in respect to the bore 402, and the ends of the depressions form stop shoulders 404 for coaction with pulley brake means mounted within the hub member 400. The hub member is provided 130

with a transverse horizontal bore 405 adjacent its periphery, into which is rotatively placed a shaft 406, having eccentric cylindrical projections 407 at each of its ends, upon which are rotatively mounted brake collars 408, designed to coact with the shallow depressions 403 and shoulders 404, of the bore 402, of the pulley 5, to positively clutch the same when forced outwardly thereagainst. Fastened to the hub member 400 at its inner face is a dished circular brake housing 410, open at one side and attached at its closed side to the hub member 400, as at 411, and is provided with a brake flange 411^a for engagement by brake shoes, hereinafter described.

A lever 412 is adjustably fastened to the inner eccentric projection 407, and at its lower end is provided with an outwardly projecting stop roller 413. A spring 414 is connected to the lower end of the lever 412 and to the housing 410 and acts through the medium of the lever 412, shaft 406 and eccentrics 407 to force the brake collars 408 into engagement with the depressions 403, and subsequently with the shoulders 404 to positively connect the pulley 5 with the hub 400.

As shown in Fig. 36, the brake collars are disengaged from the inner surface of the pulley bore, the spring 414 is under tension, and this position of the clutch parts corresponds to the initial position of the mechanism of the eyelet machine, as shown in Fig. 2. In this position, the roller 413 is engaged with a stop arm 416, depending from a laterally slidable collar 417 mounted upon the shaft 2, provided with a peripheral groove 418, and with a hub projection 419, having upon its right a peripheral involute cam 420, for engagement with the roller 413, to force the said roller and its connected lever 412 to brake collar disengaging position to release the pulley 5.

A slight rotation of the collar 417 and its depending stop arm 416, is permitted by a yielding horizontal stop shaft 422, mounted slidably in lugs 423, projecting from the casing 1, against the end 422^a of which the rear face of the depending stop arm 416 rests.

The rear end 422^b of the shaft 422 has connected to it, as at 426, a lug 428, to which is attached one end of a spring 425, the opposite end of the same being fastened as at 427 to the top of the bracket 137. The function of this spring 425 is to yieldingly counteract the shocks communicated to the depending stop arm 416, by the roller 413, as it engages the said arm. The rotation of the shaft 422 in its bearings is prevented by its attachment to the arm 428^a, the outer end of which slidably engages a pin 429 held by the rearwardmost lug 423.

Mounted upon the extended ends of the shafts 98 are brake actuating levers 430 and 431, whereof a description of each and of

their operation follows. The lever 430 is adjustably clamped upon a bushing 431, this bushing being mounted loosely upon the shaft 98 and having a brake shoe arm 432 at its outer end. The lever 430 projects rearwardly, downwardly, and in alignment with and beneath the roller 413, and is designed to be engaged with and depressed by the said roller in its rotative movement and before its engagement with the stop arm 416, to force the brake shoe 432^a attached to the brake shoe arm 432, into engagement with the brake flange 411^a. Mounted loosely between the lever 430 and brake shoe arm 432, is a stop lever 435, the lower end 436 of which engages the roller 413, to prevent its disengagement from the stop arm 416. The roller depresses this stop lever 435 against the action of a spring 437, fastened at 437^a—437^b respectively to the brake lever 430 and to the said stop lever.

The brake actuating lever 431 is mounted loosely near the end of and upon the rearwardmost shaft 98 and extends vertically downward, its front face 440 engaging the end 422^b of the shaft 422 by which it is forced outwardly to bring the brake band 445^a into engagement with the brake flange 411^a when the roller 413 strikes the projection 416 to positively prevent further rotation of the shaft 2. A pin 441 projects laterally from the lever 431 and contacts a compression spring 442, adjustably mounted as at 443 in a lower depending arm 444 of the brake shoe lever 445, the said brake shoe lever being loosely mounted for oscillation on the shaft 98, adjacent the outer face of the lever 431. A horizontal arm 446 projects rearwardly from the brake shoe lever 445 and at its outer end is provided with an upwardly extending adjustable set screw 447, the head 448 of which is designed for engagement with and depression by an arm 450, adjustably clamped at its hub end to the end of a rotatable shaft 451, parallel with and above the shaft 422, and held in a bearing 453, of the casing 1. At the forward end of the shaft 451 is adjustably clamped a depending tripping arm 454, provided at its lower end with a pin 455, engaging the groove 418 of the collar 417. Upon the depression of the arm 450, by the operator, the collar 417 is forced to the left to disengage the stop arm 416 from its engagement with the roller 413, to allow the brake collars 408 to engage the hub depression of the constantly rotating pulley 5, to set the eyelet machine in operation. The arm 450 is depressed by the operator through means of a treadle, (not shown), connected to a chain 460, the upper end of which has a hook connection 461, with the outer end of the lever 450.

The brake actuating levers 430 and 431 are, in rapid succession caused to bring their respective brake shoes into contact with the

brake flange 411^a, the lever 430 being first actuated by the roller 413 as it approaches for engagement with the arm 416, and the lever 431 being thereafter immediately actuated as a result of the collision of the roller 413 with the arm 416, the rearward motion of the said arm being communicated to the shaft 422 and from it to the lever 431.

A counter stop 457 is attached within the 10 groove 418 in substantially diametrical relation to the stop arm 416, and abuts the end of the shaft 451, its function being to prevent counter-rotation of collar 417, after the stop arm 416 has been engaged by the roller 413, 15 and when the shaft 422 is retracted by the spring 425.

An arm 465, projecting vertically from the hub of the arm 450, is provided with a spring 466, attached at 467 to its upper end, and at 20 468 to the casing 1, the function of the said spring and arm being to automatically return the projection 416 to a position for engagement with the roller 413 when desired.

When the roller 413 is released from contact with the stop arm and moves inwardly under the action of the spring 414, its inner flat face contacts the outer face of the arm 416, and slides thereagainst, its further inner movement being prevented by the edge of 30 a circular washer 419^b, equal in diameter to the diameter of the hub projection 419; these contacts are maintained until the forward peripheral edge of the roller passes the rear vertical edge of the arm 416, at which time the 35 collar 417 and attached involute cam 420 are thrown to the right by the action of the spring 466, to bring the cam into a position for engagement by the roller 413, to force the same outwardly, to release the brake collars 40 408. This release takes place before the shaft 2, and correlated mechanism reaches its initial position, the momentum of the machine completing the initial setting of the said mechanism.

45 In Figs. 39 to 42 inclusive, I have illustrated a form of punch block for use in stock, upon which is sewed a "military stay" strip. Much difficulty is experienced in setting eyelets in these strips, inasmuch as the right or 50 fair side of the upper, faces downwardly, and consequently provides no means whereby the worker can locate the point of insertion of the eyelet with sufficient accuracy. I overcome the above difficulty by providing a circular punch block 500, provided upon its upper face with a groove 501, the width of 55 which is sufficient to allow an easy sliding movement of the "stay" therewithin. The punch block is provided with a depending 60 pivot-stud 502, which traverses the work table, to allow a rotative movement of the attached block. A broad-headed screw 503, is threaded into the lower end of the stud 502, the head of the same engaging the under side 65 of the work table, to prevent withdrawal or

displacement of the block, but to allow its free rotative movement conformably to the requirements, as determined by the curvature of the "stay" strip 505, sewed to the upper 70 506.

As shown in Figs. 41 and 42, the "stay" is inserted and guided in the groove 501, of the pivoted punch block.

The above described construction provides a means for accurately and automatically 75 guiding the "stay" to successive eyelet-setting positions.

Having described my invention, I claim:

1. In an eyelet machine, a tool carrying frame, a combined punching and setting tool, 80 a setting tool opposing said first named tool, each mounted for reciprocation in said guide frame, the central axes of the said tools being in fixed alignment, means for reciprocating said tools at different speeds, and means for feeding said frame.

2. In an eyelet machine, a tool carrying frame, a combined stock-punching and eyelet-setting tool, an eyelet setting-tool opposing said first named tool, each mounted for reciprocation within said guide frame, the central axes of said tools being in fixed alignment, means for causing lateral reciprocation of said frame, and means for operating said tools at different speeds for a stock 95 punching and an eyelet setting operation.

3. In an eyelet machine, a tool carrying frame, a combined stock-punching and eyelet-setting tool, an eyelet setting-tool opposing said first named tool, each mounted for reciprocation in said frame, the central axes of said tools being in fixed alignment, means for varying the feed throw of the said frame, and means for operating said tools at different speeds to punch the stock and set an eye- 100 let within the punched opening.

4. In an eyelet machine, a tool carrying frame, capable of lateral reciprocatory motion, a combined stock-punching and eyelet-setting tool, an eyelet setting-tool opposing 110 said first named tool, each tool mounted for reciprocatory motion within said frame, the central axes of said tools being in fixed alignment, means for operating said tools at different speeds for stock-punching and eyelet-setting operations, and means for varying the length of the reciprocatory motion of said unitary punch, feed, set and guide frame.

5. In a machine for inserting fasteners, a tool head, two oppositely disposed cooperating tools mounted in positive alignment in said head, means for reciprocating said head; means for actuating one of said tools to engage the work and feed it when said head is reciprocated, and means for actuating the 125 other of said tools to present a fastener to the work fed by the other tool.

6. In a machine for inserting fasteners, a tool head, two oppositely disposed cooperating tools mounted and movable in positive 130

alignment in said head, means for reciprocating said head, means for actuating one of said tools to engage the work and feed it, and means for actuating the other of said tools to present a fastener to the work so fed.

7. In a machine for inserting fasteners, a tool head, two oppositely disposed cooperating tools mounted in positive alignment in said head, means for actuating one of said tools to engage the work and feed the same when said head is reciprocated, means for actuating the other of said tools to present a fastener to the work so fed, means for reciprocating said head, and means for varying the length of said reciprocating movement.

8. In a machine for inserting fasteners, a tool carrying head having relatively opposite bearings and an intermediate work receiving throat, opposing co-operating tools respectively supported and reciprocable in said bearings, means for reciprocating said tools at different speeds one from the other, and means for supporting and guiding said head for sliding reciprocating movement in a work feeding direction.

9. In a machine for attaching annular fasteners, opposed upper and lower cooperating tools, a head unitarily carrying said tools and supporting them in positive alignment and registration, a race-way for supplying fasteners, means for actuating the upper tool to engage through work disposed between the tools for advancing the same, and means for actuating the lower tool to impale the leading fastener in the race-way while the tools move unitarily with the head in a work advancing direction, said lower tool being arranged to center and guide the impaled fastener into engagement with the upper tool.

10. In a machine for attaching annular fasteners, opposed upper and lower co-operating duplex tools, a head carrying said tools and supporting them in positive alignment and registration, a raceway for supplying fasteners, means to move said tools unitarily with the head during a work feeding movement, an element on each of said tools adapted for co-operation in attaching a fastener to the work, a second element on said upper tool arranged for engagement through work disposed between said tools during a feeding movement, a second element on the lower tool arranged to impale the leading fastener in the raceway and center the same relative to said first co-operating elements, and means for actuating said first co-operating elements to attach the fastener to the work.

11. In a machine for attaching annular fasteners, opposed upper and lower co-operating tools, the upper tool comprising a combined concentric punch and anvil, the lower tool comprising a yieldingly sustained spindle and a clincher concentric therewith, a head unitarily carrying said tools and supporting them in positive alignment and

registration, a raceway for fasteners, the punch of the upper tool being arranged to perforate work sustained between the upper and lower tools and engaged in the perforation for advancing the work and the spindle of the lower tool being arranged to impale the leading fastener in the raceway while the tools move unitarily with the head in a work advancing direction and to center and guide the same relative to the anvil and clincher, and means for reciprocating said tools in timed relation and independent functioning degrees.

12. In a machine for attaching annular fasteners, two co-operative constantly aligned setting tools, means to move said tools unitarily laterally and to cause one to engage work for advancing the same, the other to transfer a fastener from a raceway with the work advancing movement and both to co-operate in attaching the fastener to the work, and a raceway for supplying fasteners.

13. In a machine for attaching annular fasteners, means for moving a tool holding frame for supporting opposing tools in co-operative alignment laterally, means to reciprocate opposing cooperative tools in said frame, a work supporting table interposed between said tools having a punch block and a tool receiving aperture, one of said tools cooperating with said punch block for punching an aperture in work for the reception of a fastener and for tool engagement with the work to feed the same during the lateral movement of said frame, the second tool being adapted to transfer a fastener from a race-way with the work feeding movement, and the tools cooperating through the table aperture in attaching the fastener to the work, and a race-way for supplying fasteners.

14. In a machine for inserting fasteners, a tool-head carrying oppositely disposed co-operating tools in positive alignment, means for supporting and guiding said head for movement at right angles to the movement of the tools, means for moving said head, a raceway for supplying fasteners, and means for actuating one of said tools carried by said head to feed the work and the other to transfer a fastener from the race-way with the movement of said head.

15. In a machine of the class described, a tool carrying frame having opposing aligned tool supporting bearings and a work-receiving throat therebetween, said frame being movable transversely to the working strokes of the tools, reciprocable cooperating tools respectively supported in the bearings of said frame, means for actuating one of said tools to feed the work and the other to present a fastener to the work, means for transversely reciprocating said frame, and means for varying the reciprocating stroke of said frame.

16. In a machine of the class described, a

forked frame, cooperating oppositely disposed tools mounted for constant alignment in said frame, means for actuating one of said tools to feed the work and the other to

5 present a fastener to the work, a stationary work-support between said tools, means for supporting and guiding said frame for reciprocating movement, and means for reciprocating said frame in a straight path
10 transversely to the movement of said tools.

17. In a machine of the class described, a frame carrying oppositely disposed depressible co-operating tools for operating upon the work interposed between the tools, said frame
15 being reciprocable in a path transverse to the paths of said tools for feeding work engaged by the tools, means for reciprocating said frame, comprising a rotary cam and a lever mechanism co-operating with said cam
20 and in continuous connection with said frame, a fulcrum head co-operating with said lever mechanism and slidably thereon, and means for moving said fulcrum head in
25 relation to said lever mechanism for varying the length of the reciprocating stroke imparted to said frame.

18. In a machine of the class described, a frame carrying oppositely disposed longitudinally movable co-operating tools for operating upon the work interposed between said tools, said frame being reciprocable in a path transverse to the paths of said tools, means for reciprocating said frame comprising a lever mechanism in continuous connection with said frame and including a lever, a fulcrum head slidably mounted on said lever and adapted to serve as a fulcrum therefor, and means for moving said fulcrum head upon said lever to change the fulcrum there-
30 of and the effective stroke of said lever and thereby to regulate the length of the reciprocating stroke imparted to said frame.

19. In a machine of the class described, a movable frame carrying oppositely disposed longitudinally movable co-operating tools for operating upon the work interposed between said tools, means for reciprocating said frame for feeding the work engaged by said tools comprising a lever mechanism connected to
45 said frame and including a lever having a fulcrum head slidable thereon for varying the length of the transmitting movement of said lever and the work-feeding stroke of said frame, and means for moving said fulcrum head on and in relation to said lever independently of the operation of the machine.

20. In a machine of the class described, a movable frame carrying oppositely disposed longitudinally movable co-operating tools for operating upon the work interposed between said tools, means for reciprocating said frame for feeding the work engaged by said tools comprising lever connected with said frame, including a lever, a fulcrum head slidably mounted on said lever and serving as a ful-

crum therefor, and treadle-operated means for moving said fulcrum head upon said lever for varying the length of the work-feeding stroke of said frame.

21. In a machine of the class described, a movable frame carrying oppositely disposed depressible co-operating tools for operating upon the work interposed between said tools, means for reciprocating said frame in a straight path for feeding the work engaged by said tools comprising lever mechanism connected to said frame and including a lever, a fulcrum head slidably mounted upon said lever and movable thereon for changing the fulcrum therefor, and treadle-operated means for moving, independently of the operation of the machine, said fulcrum head in relation to said lever to vary the length of the work-feeding stroke of said frame.

22. In a machine of the class described, a movable frame carrying oppositely disposed depressible co-operating tools for operating upon the work interposed between the said tools, means for reciprocating said frame in a straight path for feeding the work engaged by one of said tools only, comprising lever mechanism connected to said frame, including a lever, a fulcrum head slidably mounted upon said lever and serving as a fulcrum therefor, and treadle-operated means for moving said fulcrum head in relation to said lever to change the fulcrum point thereof for varying the effective throw of said lever.

23. In a machine of the class described, a movable C-frame carrying two oppositely disposed depressible co-operating tools for operating upon the work interposed between said tools, means for reciprocating said frame in a straight path for feeding the work engaged by said tools, comprising lever mechanism connected to said frame and including a lever, a fulcrum head slidably mounted upon said lever, means for sliding said fulcrum in relation to said lever to change the fulcrum point thereof and the effective throw of said lever, and a treadle operable at the will of the operator independently of the operation of the machine for moving said fulcrum head.

24. In a machine of the class described, a movable frame carrying two oppositely disposed longitudinally movable tools adapted for co-operative action upon the work between them, means for reciprocating said frame to feed the work engaged by said tools, and means for operating said tools, each of said operating means being provided with an anchoring plate adapted for engagement with a notch in one of said tools to permit said tool to be moved laterally with said frame without being disconnected from its respective operating means.

25. In a machine of the class described, a tool supporting frame movable in a direction for advancing the work engaged by the

- tools, two oppositely disposed co-operative tools mounted in permanent alignment in said frame and movable unitarily therewith, means for actuating one of said tools, a guided 5 plunger for actuating the second of said tools, said second tool being removably and slidably connected with said plunger to permit said tool to move laterally with said frame and in relation to said plunger, a lever 10 for reciprocating said plunger, and a coupling connecting said lever and plunger, said coupling being adjustable to regulate the throw of said tool.
26. In a machine of the class described, a 15 movable tool carrying frame, oppositely disposed cooperating tools mounted in said frame movable independently in directions toward and from each other and transversely unitarily with said frame, means for reciprocating the first of said tools, a guided plunger removably connected with the second of said tools, means for actuating said plunger having a hinged connection therewith, whereby the plunger may be swung for disconnection 20 with said second tool for tool removal, and means for operating said tools at different speeds.
27. In a machine of the class described, a movable tool carrying frame, oppositely disposed 25 cooperating tools mounted in said frame movable independently in directions toward and from each other and transversely unitarily with said frame, means for reciprocating the first of said tools, a guided plunger removably connected with the second of said tools, means for actuating said plunger, and a turnbuckle pivotally connecting said means and plunger adjustably for adjusting the tool reach, said turnbuckle providing a hinge for swinging the plunger to a tool releasing and disconnecting position.
28. In a machine of the class described, a tool carrying frame, oppositely disposed co-operating tools mounted in said frame in permanent alignment and registration, a lever 45 for reciprocating one of said tools, means for adjusting the axis of said lever for adjusting the reach of said tool, and means for reciprocating the second of said tools in timed relation with the said first tool but at a different speed.
29. In a machine of the class described, a tool-carrying frame, oppositely disposed co-operating tools mounted in said frame, means 50 for reciprocating said frame, a lever for reciprocating one of said tools, the tool having a tongue and groove sliding connection with the lever permitting the tool to be removed laterally in relation to the lever without disconnection therefrom, an eccentric bushing mounted in said lever at the fulcrum point and journaled upon the axis of said lever, means for rotatively adjusting the bushing within the lever to regulate the effective 55 stroke of the lever, and means for locking said bushing in adjusted position.
30. In a machine of the class described, a movable tool carrying frame for advancing the work, oppositely disposed co-operating tools mounted in said frame, a shaft, a lever 60 fulcrumed on said shaft for reciprocating one of said tools, a mounting for said shaft adapted to permit longitudinal movement of the shaft for disconnecting the lever and shaft, and a sliding connection between the lever and tool permitting tool movement and adapted for disconnection after the shaft and lever have been disconnected.
31. In a machine of the class described, a movable tool carrying frame for advancing the work, oppositely disposed co-operating tools mounted in said frame, a shaft, a lever 65 fulcrumed on said shaft for reciprocating one of said tools, an eccentric bushing between said shaft and lever, means for rotatively adjusting and locking the bushing for adjusting the reach of the tool connected therewith, a mounting for said shaft adapted to permit removal thereof for disconnecting the lever and shaft, and a sliding connection between the lever and tool permitting tool movement and adapted for disconnection after the shaft and lever have been disconnected.
32. In a machine of the class described, a tool carrying frame, oppositely disposed co-operating tools mounted in said frame, means for reciprocating one of said tools at differentiated rates of forward and retreat strokes for a cooperative slow forward stroke and a quick retreating stroke, comprising a 80 rotative driving and a driven member having relative eccentric axes, a slide block slidable on one of said members in an arc intersecting the axis of the member, a crank connecting with the second member and said slide block, and lever mechanism connecting said crank and tool and converting rotating into reciprocating motion.
33. In a machine of the class described, a tool carrying frame, oppositely disposed co-operating tools mounted in said frame, means for reciprocating one of said tools at differentiated rates of forward and retreat strokes, comprising rotative driving and driven members, having relative eccentric axes, a crank 95 element rotative with one of said members and movable independently thereof in an arc intersecting the axis of said member, a crank rotative with the second member and having a swivel connection with said first crank element, and lever mechanism connecting said second crank and tool and converting rotary into reciprocating motion.
34. In a machine of the class described, a tool carrying frame, oppositely disposed co-operating tools mounted in said frame, means for reciprocating one of said tools at differentiated rates of relative forward and 100
- 105
- 110
- 115
- 120
- 125

retreating strokes, comprising rotative driving and driven members having relative eccentric axes, a crank rotatively connecting said members fixed to one and swivelled and movable upon the second in an arc bisecting the axis of the second member, and lever mechanism connecting said crank and tool.

35. In a machine for inserting fasteners, a tool head carrying oppositely disposed co-operating tools in positive alignment, means for supporting and guiding said head for sliding movement at right angles to the movement of the tools to feed work engaged by the tools, and means for reciprocating said tools at different speeds.

36. In a machine for inserting fasteners, a tool head carrying oppositely disposed co-operating tools in positive alignment, means for supporting and guiding said head for sliding movement at right angles to the movement of the tools to feed work engaged by the tools, means for reciprocating said head, and means for operating said tools at different speeds.

37. In a machine for inserting fasteners, a tool head carrying oppositely disposed co-operating tools in positive alignment, means for supporting and guiding said head for sliding movement at right angles to the movement of said tools, means for reciprocating said head, means for varying the length of said reciprocating movement of said head, and means for operating said tools at different speeds.

38. In a machine for inserting fasteners, a tool head carrying oppositely disposed co-operating tools, means for reciprocating said head to feed the work, and means for operating said tools at different speeds.

39. In a machine for inserting fasteners, a tool head carrying oppositely disposed co-operating tools, means for reciprocating said head to feed the work, means for varying the length of said reciprocating stroke, and means for operating said tools at different speeds.

40. In a machine for inserting fasteners, a tool head carrying oppositely disposed co-operating tools, one of said tools being a combined punching and setting tool and the other a setting tool, means for reciprocating said head to feed the work, and means for operating said tools at different speeds.

41. In a machine for inserting fasteners, a tool head carrying a combined punching and setting tool and a setting tool, said tools being oppositely disposed for cooperation and in alignment, means for reciprocating said head to feed the work, and means for operating said tools at different speeds.

42. In a machine for inserting fasteners, a tool head, a combined punching and setting tool and a setting tool mounted in alignment with each other in said head for cooperative action, means for reciprocating said tools at

different speeds to punch the work and insert a fastener therein, and means for moving said head in a direction transverse to the movement of said tools in order to feed the work while it is engaged by said punching and setting tool.

43. In a machine for inserting fasteners, two cooperating constantly aligned setting tools movable unitarily laterally, means for actuating one of said tools to engage work for advancing the same and the other to transfer a fastener from a raceway with the work advancing movement, means for operating said tools at different speeds for attaching the fastener to the work, and a raceway for supplying fasteners.

44. In a machine for inserting fasteners, two constantly aligned setting tools movable unitarily laterally to feed the work, and means for moving said tools longitudinally at different speeds for cooperative action in attaching a fastener to the work.

45. In a machine for inserting fasteners, two constantly aligned setting tools movable unitarily laterally to feed the work, means for moving said tools at different speeds longitudinally for cooperative action in attaching a fastener to the work, and means for varying the length of said lateral movement.

46. In a machine for inserting fasteners, two constantly aligned setting tools movable unitarily laterally in a straight path to feed the work, and means for moving said tools at different speeds longitudinally for cooperative action in attaching a fastener to the work, and means for varying the length of said lateral movement.

47. In a machine of the class described, a tool carrying frame, oppositely disposed co-operating tools mounted in said frame, means for reciprocating one of said tools at differentiated rates of forward and retreat strokes for a cooperative slow forward stroke and a quick retreating stroke, comprising a rotative driving member and a rotative driven member in eccentric relation, a slide block slideable on said driving member in an arc intersecting the axis of said member, a crank connecting said driven member and said slide block, and lever mechanism connecting said crank and said tool.

48. In a machine of the class described, a tool carrying frame, oppositely disposed co-operating tools mounted in said frame, means for reciprocating one of said tools at differentiated rates of forward and retreat strokes comprising a rotative driving member and a rotative driven member in eccentric relation, a slide block slideable on said driving member in an arc intersecting the axis of said member, a pin fixed on said driven member and entering said slide block, and lever mechanism connecting said pin and said tool.

49. In a machine of the class described, a tool carrying frame, oppositely disposed co-

operating tools mounted in said frame, means for reciprocating one of said tools at differentiated rates of forward and retreat strokes comprising a rotative driving member and a 5
5 rotative driven member in eccentric relation, said driving member being provided with a groove intersecting the axis of said member, a slide block slidable in said groove, a crank rotatively connecting said members fixed to 10
10 the driven member and swivelled on said slide block, and lever mechanism connecting said crank and said tool.

50. In a machine of the class described, a tool carrying frame, oppositely disposed co- 15
15 operating tools mounted in said frame, means for reciprocating one of said tools at differentiated rates of relative forward and retreat strokes comprising rotative driving and driven members in eccentric relation, a 20
20 crank rotatively connecting said members and fixed to one and swivelled and movable upon the other in a path intersecting the axis of said other member, and lever mechanism connecting said crank and said tool.

51. In a machine for inserting fasteners, the combination of a tool head, two oppositely disposed co-operating tools mounted and movable in positive and permanent alignment in said head, means for reciprocating 30
30 said head, means for actuating one of said tools to punch and feed work, and means for actuating the other of said tools to present a fastener to the work so fed.

52. In a machine for inserting fasteners, two constantly aligned setting tools movable 35
35 unitarily laterally in a straight path to feed work, and means for reciprocating said tools longitudinally to attach a fastener in the work, the reciprocating means for each tool 40
40 being independent of the reciprocating means for the other of said two tools to permit the two tools to be operated at different speeds and with different length of stroke.

53. In a machine for inserting fasteners, two constantly aligned setting tools movable 45
45 unitarily laterally in a straight path to feed work, and means for reciprocating said tools longitudinally, to attach a fastener in the

work, the reciprocating means for each tool being independent of the reciprocating means 50 for the other of said two tools.

54. In a machine for inserting fasteners, the combination of a C-frame, two constantly aligned co-operative tools mounted for reciprocation in said frame, means for reciprocating said frame laterally in a straight path to feed the work, means for reciprocating said tools to punch the work and set a fastener therein, and means for varying the length of movement of said frame without interfering with the operation of the machine.

55. In a machine for inserting fasteners, the combination of a C-frame, two constantly aligned tools mounted for reciprocation therein, one of said tools being adapted for 65
65 punching the work, for feeding the same by engagement therewith when said frame is reciprocated and for co-operating with the other of said tools for setting the fastener in the work, means for reciprocating said frame, 70
70 and means for operating said tools.

56. In a machine of the class described, the combination of a fixed shaft, a C-frame mounted and laterally reciprocable on said shaft and adapted for carrying a pair of co-operating tools in fixed alignment for operating on work interposed between them and the two arms of the said frame, a transverse guide shaft fixed on said C-frame and beneath and parallel to said fixed shaft, bearings for said 80
80 guide shaft, and means for reciprocating said frame on said fixed shaft.

57. In a machine of the class described, the combination of a fixed shaft, a C-frame supported by and laterally reciprocable on 85
85 said shaft, a pair of cooperating aligned tools longitudinally movable in said frame, one in each arm thereof, means for operating said tools without interfering with the reciprocation of said frame, a guide shaft carried by 90
90 said frame in parallel relation to said fixed shaft, bearings for said guide shaft, and means for reciprocating said frame.

In witness whereof, I hereunto subscribe my name.

WILLIAM F. LAUTENSCHLAGER.
